UNITED STATES PATENT OFFICE

2,547,410

COIN CARRIER

Charles Priesmeyer, Park Ridge, Ill., assignor to
Meyer & Wenthe, Inc., a corporation of Illinois

Application November 16, 1948, Serial No. 60,190

7 Claims. (Cl. 133—5)

1

This invention relates to a coin carrier or so-called "change maker" for coins or tokens of a given uniform character with provision so that a predetermined number of coins of the same denomination may be ejected into the hand of the street car conductor or bus conductor, or other fare collector, to make change or to deliver a certain number of tokens, rapidly and accurately, the invention being particularly adaptable to the portable type of device of this class which may be carried on a strap or belt worn by the operator or mounted in readily accessible position upon a fare box or other vehicle part.

The invention is importantly inclusive of means whereby the number of predetermined coins or tokens ejected upon one operation of the changer may be readily varied in response to, say, changes of city ordinance, fare rates, or other regulations, and whereby, more especially, selective changes for such variations may be made by the operator without the necessity of removing or loosening bolts, screws or other fastening elements.

In general, the invention aims to provide an improved and simplified coin changer of the class referred to, which may be produced in large quantities at a minimum of cost and with a minimum number of parts.

These and other objects and advantages will be apparent from the following description, taken together with the accompanying drawings, of an illustrative embodiment of the invention, and in which drawings

Figure 1 is a front elevational view of a structure following the present invention, in which for clearness of description the dimensions shown may be somewhat larger than commonly employed;

Figure 2 is a vertical sectional view taken on the line 2—2 of Fig. 1, looking in the direction of the arrows, a stack of coins or tokens being shown in dotted lines;

Figure 3 is a horizontal cross section looking downward on the line 3—3 of Fig. 2, but with the coins omitted;

Figure 4 is a partial vertical section taken on the line 4—4 of Fig. 2;

Figure 5 is a vertical sectional view taken on the line 5—5 of Fig. 2;

Figure 6 is a view somewhat similar to Fig. 2 but showing the lower part of the structure in an alternative position of the parts, for discharging coins;

Figure 7 is a further fragmentary view similar to Fig. 6 but showing a selective arrangement of the parts in which a fewer number of coins are ejected;

Figure 8 is a sectional view, somewhat similar to Fig. 4, of the parts when arranged for the ejection of a still fewer number of coins;

Figure 9 is a sectional view somewhat similar to

2

to Fig. 8 but showing the arrangement of the parts when only a single coin is desired to be ejected;

Figure 10 is a plan view on a somewhat reduced scale of the main ejector ward;

Figure 11 is a similar plan view of the detent ward; and

Figure 12 is a similar view of one of the auxiliary wards which may be selectively either ejector wards or detent wards.

Referring in detail to the illustrative construction shown in the drawings, the numeral 11 indicates a support or holder for a vertical coin magazine 12 in the form of a tube having an inner diameter corresponding to the diameter of coins to be received therein in a vertical stack. The holder 11 has a top 13 which retains the tube 12 in position at that end and this top commonly has a somewhat hopper shape mouth 14 terminating in a slot 15 through which the magazine is loaded with coins, the tube having sight openings 15a at its front through which the presence of coins may be observed.

At its lower end, the tube 12 rests upon a ward frame 16 which is in the form of an inverted channel member having side walls 17 and 18 and top wall 19 upon which the tube 12 rests, this top wall having a circular opening 20 in register with the interior of the tube and of the same diameter.

The ward frame 16 is in turn supported on the base 21 of the holder, which latter has the back 22 and sides 23, being open at the front, the sides being arcuately cut back as at 23a for convenience. The holder base 21 has a semi-circular cutback 24 in its front edge which is disposed forwardly of the tube 12 for facilitating ejection of the coins as later described.

In accordance with the present invention, the ward frame 16 has reciprocable or slidably rearwardly and forwardly therein a plurality of coin rings or wards presently more particularly described, the relationship of which may be varied by the user of the device. In the present instance, these include a main ejector ward 25, a plan view of which is shown in Fig. 10; a detent ward 26, a plan view of which is shown in Fig. 11; and a plurality of auxiliary wards 27, in this instance three, a plan view of one of which is shown in Fig. 12. Each of these wards has a circular coin opening 25a, 26a, and 27a respectively which are adapted to register with each other and with the interior of the tube 12 when the wards are at their rearmost position for the passage of coins therethrough. The main ejector ward 25 and the auxiliary wards 27 are plates of a thickness corresponding to the thickness of a coin or token of the diameter intended to be carried in the tube 12. The detent ward 26 may be of the same thickness, as here shown.

The main ejector ward 25 has a tail piece 28 in which is a slot 29 loosely receiving the lower end 30 of a pusher arm 31 which is hinged at 32 to the back 22 of the holder. A convenient hinge mechanism may be provided by striking forwardly as at 33 the margins of cuts 34 in the holder back to receive trunnions 35 on the upper end of the pusher arm. An actuating lever 36 for the pusher arm is similarly hinged as at 37 on the holder back 22 at the lower end of the lever and has a trigger extension 38 which terminates in a finger or thumb piece 39 accessible to the hand of the operator at the front of the device and at the side of the tube 12.

To retract the pusher arm 31 and with it the main ejector ward 25, resilient means are provided represented in the present instance by the leaf spring 40 which is riveted as at 41 to the upper part of the holder back 22 and the free resilient lower end of which presses on the pusher arm 31. At this time, the actuating lever 36, trigger extension 38 and thumb piece 39 are raised to the position shown in Figs. 1 and 2.

When the thumb piece 39 is pressed upon by the operator, the actuating lever 36 drops forwardly against the pusher arm 31 to cam or move the lower end of this arm forwardly against the resilience of the leaf spring 40 and to cause reciprocation or sliding movement of the main ejector ward 25. The ejector ward tail piece 28 is desirably upturned as at 42 to guard against the lower end 30 of the pusher arm slipping out of the slot 29. Selective means are provided for interlocking the auxiliary wards for or from reciprocation, by inverting the wards as desired.

The auxiliary wards 27 rest on the main ejector ward 25, one above the other, and have struck tongues 43 at each side thereof which project to one face of each ward leaving notches 44 in the opposite face of the auxiliary ward. The main ejector ward 25 has notches 45 in its side edges which when the auxiliary ward next above it has its tongues 43 facing downwardly, receive the tongue 43 in the notches 44 to interlock this particular auxiliary ward with the main ejector ward to cause sliding movement therewith.

Similarly, this may be effected of all of the auxiliary wards 27, in this instance all three of them, as shown in Figures 1 to 6 inclusive, by having all of the auxiliary wards arranged with their tongues 43 facing downwardly, the two uppermost auxiliary wards having their tongues 43 interlocked with the notches 44 in an auxiliary ward next therewith.

Superposed on the auxiliary ward is the keeper ward 26 which is not interlocked at any time to slide with the main ejector ward. However, the keeper ward 26 is, in accordance with the present invention, desirably removable from the ward frame 16 to facilitate selective arrangements of the auxiliary wards as will be explained. For this purpose, the releasable detent 46 is provided, in this instance in the form of a yoke member hinged by each horn thereof as at 47 on the side walls 17 and 18 of the ward frame 16 and thus adapted to drop down into position in front of the forward edge of the keeper ward 26. When in this position, it retains the keeper ward in register with the tube 12 when the main ejector ward, and, if so arranged, one or more of the auxiliary wards, are slid forward when the thumb piece 39 is pressed upon as shown in Fig. 6. The pusher arm 31 moves freely between the legs 51 of the keeper ward. The yoke 46 is desirably arcuate to conform to the arcuate front

edges of the wards and has a horizontal rearward extension 48 which limits its downward movement when in position as a detent, by engagement with the ward frame.

When a stack of coins, a few of which are indicated by the dotted lines 49 (Fig. 2) are in the tube, having been inserted therein through the mouth 14 to fill or substantially fill the tube, the coins will drop down by gravity to occupy not only the lower end of the tube but also a coin will fall into place in the coin opening 25a in the main ejector ward 25 and into each of the coin openings 27a in the three auxiliary wards 27. For this purpose, they will drop through the coin opening 26a in the keeper ward 26, and, incidentally, a coin will also take a position in this keeper opening 26a.

When, now (the parts being arranged as shown in Figs. 1 to 6 inclusive), the thumb piece 39 is pressed upon by the operator, the main ejector ward 25 will be slid forwardly and with it all three of the auxiliary wards 27, each (that is, the main ejector ward and the auxiliary wards) carrying with it the coin which is disposed in its coin opening. When the main ejector ward and the auxiliary wards move forwardly, under the influence of the actuating lever 36 to the position shown in Fig. 6, the coin openings 25a and 27a will then be brought into register with the coin cutout 24 in the holder base 21, and four coins (the coins carried by the main ejector ward and the three auxiliary wards) will drop by gravity into the hand of the operator, which it may be assumed is there to receive them. Here, all the auxiliary wards function as ejector wards.

Upon release of the thumb piece 39, the main ejector ward and the three auxiliary wards interlocked therewith are retracted or reciprocated rearwardly under the influence of the spring 40, and when again brought into register with the tube 12, as in Fig. 2, four more coins will drop by gravity, one into each of the coin openings 25a of the main ejector ward and the coin openings 27a of the three auxiliary wards, to repeat the operation of ejecting another group of four coins if desired.

If now it be desired to change the device so that only three coins will be ejected at a given operation of the thumb piece 39, the operator may himself, following the present invention, readily make the following changes after first temporarily ejecting all of the coins from the magazine:

By simply lifting the detent 46 and inserting a pin or pencil point in the hole 50 in the forward margin of the detent ward 26 this may be slid out of the device. When this is removed, it may be used as a tool to remove the auxiliary wards. For this purpose, the legs 51 of the keeper ward are beveled at their rear ends as at 52 so that these legs may be slid under the auxiliary wards and the latter lifted out of interlock with the main ejector ward, whereupon they may be slid forwardly out of the device.

This having been done, the wards are rearranged by the operator somewhat as shown in Fig. 7 thus: The two lowermost wards are arranged with their tongues 43 facing downwardly. This locks the two lowermost wards to the main ejector ward and to each other to slide in unison. The topmost auxiliary ward is, however, inverted and arranged with its tongues 43 facing upwardly and these tongues are then received inside the side notches 53 in the keeper ward 26.

Thus, when the keeper ward 26 and this uppermost of the auxiliary wards are slid into the

housing frame 16, and the detent 46 lowered into position in front of the front edge of the keeper ward, the uppermost auxiliary ward 21 will now remain stationary with the keeper ward and with the tube 12 when the trigger is pressed. Since again coins in the tube will have fallen by gravity into each of the coin openings in the wards when these are in register, when the trigger is pressed upon only two of the auxiliary wards will slide forward with the main ejector ward and thus only three coins will be ejected into the hand of the operator, as shown in Fig. 7. Here only two of the auxiliary wards function as ejector wards, the third or uppermost functioning as a keeper ward.

Similarly, when only two coins are desired to be ejected, the operator may rearrange them as shown in Fig. 8 in which the two uppermost auxiliary wards are interlocked with the keeper ward and with each other and only the lowermost auxiliary ward is interlocked with the main ejector ward, so that only the latter and one auxiliary ward will slide forwardly when the trigger is pressed. Here the upper two auxiliary wards function as keeper wards and only the lowermost as an ejector ward.

Similarly, if only one coin is desired to be ejected, the operator may arrange the wards as shown in Fig. 9 in which all three of the auxiliary wards are interlocked with the keeper ward and with each other, so that only the main ejector ward slides forward when the trigger is pressed and thus only one coin drops out. Here none of the auxiliary wards function as ejector wards but all as keeper wards.

The pusher 31 and tail piece 28—42 of the main ejector ward, can move freely between the legs of the other wards when less than all of the latter move, said legs straddling the pusher arm for this purpose while providing outer edges in which the tongues and notches are formed.

It will be understood that the holder, as seen for example in Fig. 1, may be one of several such holders arranged side by side on a mounting plate or otherwise secured together in a battery, one, say, for half-dollars, one for quarters, one for dimes, one for nickels, one for pennies, and one for tokens.

The invention is not intended to be limited to details of construction shown for purposes of illustration, and such changes may be made as fall within the scope of the appended claims without departing from the invention.

The invention having been described, what is here claimed is:

1. In a coin carrier of the class described, the combination of a holder, a base in the holder having a coin cut-out, a ward frame over said base, an ejector ward slideable on the base within the frame and having a coin opening registerable with said cut-out, a pusher arm pivoted on the holder and having an end in actuating relation with the ejector ward, a slot in the ejector ward loosely receiving said pusher end, resilient means for actuating the pusher arm, separable auxiliary wards superimposed on the ejector ward, notches at each side of the ejector ward, struck out transverse tongues on the auxiliary wards at each side on one face of each auxiliary ward, said tongues leaving notches on the opposite faces of the auxiliary wards whereby the tongues on the ward next above the ejector ward may be received in said notches in the ejector ward and tongues on the ward farther above the ejector ward may be received in the notches formed by forming the

tongues on the ward next below, the auxiliary wards having coin openings adapted to register with the ejector ward opening when the auxiliary wards are locked for movement therewith by said 5 tongues and notches, a keeper ward separably received in the frame above the uppermost auxiliary ward also having side notches receiving said tongues when the auxiliary ward next below is inverted, the keeper ward and auxiliary wards 10 having legs straddling said pusher arm a detent pivoted on the frame depressible to restrain movement of the keeper ward but elevatable to permit removal of the keeper ward with the auxiliary wards, and a tubular coin magazine carried in the 15 holder on said frame, the keeper ward having a coin opening in register with the magazine and with the coin openings in the wards when the latter are retracted.

2. In a coin carrier of the class described, the combination of a holder, a base in the holder having a coin cut-out, a ward frame over said base, an ejector ward slideable on the floor within the frame and having a coin opening registerable with said cut-out, resilient means for reciprocating 20 the ejector ward, separable auxiliary wards superimposed on the ejector ward, notches at each side of the ejector ward, struck out tongues on the auxiliary wards at each side on one face of each auxiliary ward, said tongues leaving notches in the opposite faces of the auxiliary wards whereby the tongues on the ward next above the ejector ward may be received in said notches in the ejector ward and tongues on the ward farther above the ejector ward may be received in the 25 notches formed by forming the tongues on a ward next below, the auxiliary wards having coin openings adapted to register with the ejector ward opening when the auxiliary wards are locked for movement therewith by said tongues and notches, 30 a keeper separably received in the frame above the uppermost auxiliary ward also having side notches receiving said tongues when the auxiliary ward next below is inverted, a detent pivoted on the frame depressible to restrain movement of the keeper but elevatable to permit removal of the keeper with the auxiliary wards, and a tubular coin magazine carried in the holder on said frame, the keeper having a coin opening in register with the magazine and with the coin openings in the 35 wards when the latter are retracted.

3. In a coin carrier of the class described, an ejector ward having a coin opening, separable auxiliary wards superimposed on the ejector ward, notches at each side of the ejector ward, struck 40 out tongues on the auxiliary wards at each side on one face of each auxiliary ward, said tongues leaving notches in the opposite faces of the auxiliary wards whereby the tongues on the ward next above the ejector ward may be received in said notches in the ejector ward and tongues on the ward farther above the ejector ward may be received in the notches formed by forming the tongues on a ward next below, the auxiliary wards and ejector ward having coin cut-outs adapted to 45 register when the auxiliary wards are locked for movement with the ejector ward by said tongues and notches, a keeper separably received in the frame above the uppermost auxiliary ward also having side notches receiving said tongues when the auxiliary ward next below is inverted, a detent pivoted on the frame depressible to restrain movement of the keeper but elevatable to permit removal of the keeper with the auxiliary wards, the keeper having a coin opening registerable with the coin openings in the wards.

4. In a coin carrier of the class described, an ejector ward having a coin opening and separable auxiliary wards superimposed on the ejector ward, notches at each side of the ejector ward, struck out tongues on the auxiliary wards at each side on one face of such auxiliary ward, said tongues leaving notches in the opposite faces of the auxiliary wards whereby the tongues on the ward next above the ejector ward may be received in said notches in the ejector ward and tongues on the ward farther above the ejector ward may be received in the notches formed by forming the tongues on a ward next below, the auxiliary wards having coin openings adapted to register with the ejector ward opening when the auxiliary wards are locked for movement therewith by said tongues and notches.

5. In a coin carrier or the like, in combination, a vertically disposed magazine, a coin ejector ward slidable beneath the magazine, an auxiliary coin ward superposed on the ejector ward, a keeper member superposed on the auxiliary ward, a formation on the auxiliary ward extending from one face thereof, openings in the ejector ward and keeper member respectively receiving said formation in selective positions of the auxiliary ward, the opening in the ejector ward receiving said formation in one selective position of the auxiliary ward and the opening in the keeper member receiving said formation in inverted position of the auxiliary ward, and a detent releasably holding the keeper member against sliding movement with the ejector ward, the auxiliary ward sliding with the ejector ward in its first mentioned position and being held by the keeper member from sliding movement with the ejector ward in its second mentioned position, the detent being shiftable to a position permitting sliding movement of the keeper member with the ejector ward to permit removal of the auxiliary ward for selective inversion to vary the predetermined number of coins ejected.

6. In a coin carrier or the like, in combination, a slidable coin ejector ward, an auxiliary ward superposed on the ejector ward, a keeper member superposed on the auxiliary ward, a formation on the auxiliary ward extending from one face thereof, openings in the ejector ward and keeper member respectively receiving said formation in selective positions of the auxiliary ward, the opening in the ejector ward receiving said formation in one

selective position of the auxiliary ward, the opening in the keeper member receiving said formation in inverted position of the auxiliary ward, the auxiliary ward sliding with the ejector ward in its first mentioned position and being held by the keeper member from sliding movement with the ejector ward in its second mentioned position, and a second auxiliary ward having a formation extending from one face thereof in register with said openings in the ejector ward and the keeper member, each auxiliary ward having an opening in its face opposite its face having said formation to receive the formation on the other auxiliary ward selectively.

7. In a coin carrier or the like, in combination, a vertically disposed magazine, a coin ejector ward slidable beneath the magazine, a pusher arm having an end in actuating relation with the ejector ward, an auxiliary coin ward superposed on the ejector ward, a keeper member superposed on the auxiliary ward, a formation on the auxiliary ward extending from one face thereof, openings in the ejector ward and keeper member respectively receiving said formation in selective positions of the auxiliary ward, the opening in the ejector ward receiving said formation in one selective position of the auxiliary ward and the opening in the keeper member receiving said formation in inverted position of the auxiliary ward, and releasable means holding the keeper member against sliding movement with the ejector ward, the auxiliary ward sliding with the ejector ward in its first mentioned position and being held by the keeper member from sliding movement with the ejector ward in its second mentioned position, the auxiliary ward and keeper member being cut away in the path of the pusher arm to permit free movement of the pusher arm independently of the auxiliary ward and keeper member.
